Primary Examiner — Daniel J Domino*Assistant Examiner* — Samina Vieth(74) *Attorney, Agent, or Firm* — Birch, Stewart, Kolasch & Birch, LLP(57) **CLAIM**

The ornamental design for a television receiver, as shown and described.

DESCRIPTION

FIG. 1 is a front perspective view of the television receiver showing our new design;

FIG. 2 is a front view thereof;

FIG. 3 is a back view thereof;

FIG. 4 is a left side view thereof;

FIG. 5 is a right side view thereof;

FIG. 6 is a top plan view thereof;

FIG. 7 is a bottom plan view thereof;

FIG. 8 is a back perspective view thereof;

FIG. 9 is a reference view showing the state of use that the front display part of the claimed design has been raised; and, FIG. 10 is a reference view showing the state of use that the front display part has been raised, and then rotated 90 degrees.

The broken lines depict portions of the television receiver that form no part of the claimed design.

1 Claim, 10 Drawing Sheets(56)
